E. JOHANSON

RAIL BRACE WITH TIE PLATE

Filed June 10, 1926

EMIL JOHANSON
INVENTOR

PER

Albert J. Fiske
ATTORNEY.

UNITED STATES PATENT OFFICE.

EMIL JOHANSON, OF CHICAGO, ILLINOIS.

RAIL BRACE WITH TIE-PLATE.

Application filed June 10, 1926. Serial No. 115,126.

This invention relates to improvements in a rail brace with tie plate, and has for one of its principal objects the provision of an anchor which will prevent a track rail 5 from creeping on the ties, or the tie from moving with respect to the rail.

Another important object of this invention is the provision of an anti-creeper tie plate and rail brace, particularly adapted to be 10 used at curved portions of railroad tracks or the like, whereby the tendency of the track to move in a succession of waves under rolling loads is counteracted.

Another and still further important object of this invention is means for preventing the spreading of rails, comprising a 15 simple device to be used with the rails, which will be economical of manufacture and which can be installed without altering 20 the standard equipment of the railroad.

Other and further important objects of the invention will be apparent from the disclosures in the accompanying drawings and following specification.

25 The invention, in a preferred form, is illustrated in the drawings and hereinafter more fully described.

In the drawings:

Figure 1 is a side elevation of the 30 proved rail brace and tie plate of this invention, the rail being shown in section.

Figure 2 is a top plan view of the device shown in Figure 1.

Figure 3 is a partial sectional view illustrating a slight modification of the invention.

As shown in the drawings:

The reference numeral 10 indicates generally a standard rail having the usual tie 40 12 associated therewith. In accordance with the provisions of this invention the rail 10 is to be mounted upon a tie plate 14 formed of the shape and cross section best shown in Figures 1 and 2. The tie is provided with integral downwardly extending 45 wedge-shaped or pointed members 16 which are adapted to penetrate or pierce the upper surface of the tie, thereby maintaining the tie plate in desired position.

50 The tie plate 14 has an upwardly extending longitudinal integral portion 18 against which the lower flange of the rail 10 is adapted to be positioned, and a suitable opening 20 shown in dotted lines in Figure

2, is provided in the tie plate 14 for the reception of a railroad spike 22, the head of which contacts with that portion of the rail adjacent the ledge 18 thereby maintaining that side of the rail in desired position. 55

The opposite end of the tie plate 14 is 60 formed with a depression 24 therein, in which is adapted to be positioned the rail brace proper 26 formed in the shape as shown in Figure 1, and of a size at the base to correctly fit the depression or notch 24. 65

The upper portion of the rail brace 26 is formed with an overhanging nose or the like 28 which contacts with the web of the rail and is also adapted to fit snugly under the upper flange thereof, as shown in Figure 1. 70

A transversely extending slot 30 is formed in the members 26-28 into which the lower flange of the rail 10 fits, thus forming a locking arrangement which is further secured by means of additional spikes or the like 22^a passing through the tie plate adjacent the brace 26-28 and fitted into suitable openings 20^a. 75

A slight modification of the invention is shown in Figure 3 whereby a supplementary 80 brace member 34 is positioned on the opposite side of the rail 10 and is connected to a brace 26^a similar to the brace 26 by means of a bolt or the like 36 passing through both braces and also through the rail itself. 85

It will be evident that herein is provided an anti-creeper for rails and also a tie plate which will readily accomplish the purposes of its adoption, and will prevent creeping of the rail in any direction, and which will 90 maintain the rails of the track in definite spaced relation.

I am aware that many changes may be made and numerous details of construction varied throughout a wide range without departing from the principles of this invention, and I therefore do not purpose limiting the patent granted hereon otherwise than as necessitated by the prior art. 95

I claim as my invention:

A rail brace, comprising in combination, a pair of brace elements, and a tie plate, each of said brace elements adapted to be positioned alongside the rail and contacting with the web thereof, said tie plate being provided with a depression for the reception of the rail base, one of said elements including an integrally horizontally extending 105

base of a width greater than one-half the width of the base of the rail, said base adapted to be positioned in a depression in the tie plate, said last-named depression being parallel to the depression for the reception of the rail base and lower than the same, a longitudinal groove in the base of

one of said braces for the reception of the edge of the rail base, and means for locking the rail, the brace and the tie plate into a ¹⁰ unitary structure on the tie.

In testimony whereof I affix my signature.

EMIL JOHANSON.
